UNITED STATES PATENT OFFICE.

ROBERT GIBB HUTCHISON, OF SITTINGBOURNE, ENGLAND, ASSIGNOR OF ONE-HALF
TO EDWARD LLOYD LIMITED, OF SITTINGBOURNE, ENGLAND.

PAPER AND LIKE MACHINERY.

1,040,338.

Specification of Letters Patent.

Patented Oct. 8, 1912.

Application filed July 19, 1911. Serial No. 639,268.

To all whom it may concern:

Be it known that I, ROBERT GIBB HUTCHISON, a subject of the King of Great Britain and Ireland, and residing at Sittingbourne 5 Paper Mills, Sittingbourne, in the county of Kent, England, have invented certain new and useful Improvements in and Relating to Paper and Like Machinery, of which the following is a specification.

10 This invention relates to paper making machinery and has for its object to obtain an improved drive therefor particularly with a view to the elimination of vibration, gears, tooth wheels, friction clutches, or 15 other friction devices, which are especially undesirable more particularly in connection with high speed working.

Among the objects of the present invention for example we desire to eliminate 20 toothed reducing gear which is very objectionable from the point of view of noise and also friction particularly when the same is used in connection with high speed rolls requiring a high torque for starting them or 25 for initially speeding up.

The invention consists in a drive for the parts or sections of paper-making machinery in which the desired shaft is directly driven through belts or the like which can 30 be suitably adjusted as regards tension for throwing the machine into or out of operation.

The invention also consists in a high speed drive for paper-making machinery in which 35 the individual sections are driven through belts or rope pulleys mounted on suitable short shafts which can be raised and lowered for the purpose of starting and stopping the machine.

40 The invention also consists in the improvements in and relating to paper-making machinery and particularly to high speed paper-making machinery hereinafter indicated.

45 Referring now to the accompanying dia-grammatic drawings which illustrate one manner of carrying this invention into effect, Figure 1 is a side elevation, Fig. 2 a front elevation looking in the direction of 50 the arrow of Fig. 1, and Fig. 3 a plan of an arrangement particularly suitable for high speed drives. Figs. 4 and 5 show respectively a plan of the upper driving pulleys and a plan of the lower drive of part of a

machine according to one construction of 55 the present invention. Figs. 4^a and 5^a are continuations respectively of Figs. 4 and 5.

In carrying the invention into effect in the form illustrated by way of example, rope pulleys, *a*, are mounted on a short 60 shaft, *b*, carried in suitable bearings, *c* and *d*. On the shaft *b* is also mounted a conical pulley, *e*, adapted to receive a belt *f* which passes over another pulley *g* in connection through the usual clutch *w* with the section 65 of machine to be driven. The position of the belt *f* on the shaft *g* can readily be adjusted by means of a striker, *y*, operated from the screwed rod *x*. The shaft *b* carrying the lower pulley *e*, is mounted on a 70 swinging arm *h* with balance weights *z* the arm having a circular rack *i* connected thereto, a pinion *j* being placed adjacent for coöperating with the rack to move the arm *h* about its fulcrum *k* and thereby to lift to 75 some degree the lower belt pulley *e* for the purpose of relieving the tension on the belt *f* necessary for driving purposes. The pinion *j* is operated through a shaft *l* and bevel wheel or cranks *m* and *n* placed in a convenient position with respect to the parts of the machine, in fact the machine and this gear can conveniently be placed on the floor level and the lower pulley and other parts 80 in a pit.

85 In Figs. 4 and 5 there are illustrated certain rolls or sections to which the arrangements of the above kind are applied. The pulleys, *e'*, *e²* and *e³* represent respectively the swinging pulleys represented by *e* in Fig. 1 corresponding to the couch rolls and the first, second and third press rolls respectively. Similarly the pulleys, *g'*, *g²* correspond to the upper pulleys connected to the sections or rolls to be driven.

90 In operation the lower pulley *e* is continually rotated while the drive is applied to the belt pulleys. To start the machine section the striking gear *o* connected through the vertical rod *l* and bevel wheels *m* and *n* to the pinion *j* is operated so to move the lever *h* carrying the lower belt pulley *e* that sufficient tension is put on the belt connecting the upper and lower pulleys *g* and *e* respectively to drive the upper pulley *g* and *e* thereby drive the section of the machine 95 connected thereto.

100 It will be understood that the above ex-

ample is given as one form only and modifications may be made as desired, for instance instead of the gear arrangement represented by *v* a simple hand wheel may be provided at the top of the shaft *b* and the necessary reduction be obtained either at the gears *m* and *n* or at some other suitable gearing. Also instead of using a jockey pulley *e* suitable clutches may be employed, although less satisfactory. The degree of tension on the belt can be adjusted by means of notches marked on the striking gear or in any other convenient manner.

It will be appreciated that according to the present invention a simple and effective means of starting and stopping the sections of a paper making machine is obtained enabling high speeds to be utilized without vibration or gearing troubles and with little lubrication and also permitting ordinary belts to be employed. Further no clutches are needed and because the belt is at rest when the machine is stopped the life of the belt is lengthened. Further great steadiness in running is insured and little power required to drive the machine.

Having now described my invention what I claim as new and desire to secure by Letters Patent is:—

30. 1. In paper making machinery, a section drive comprising an arm, means for swinging the same, and a pulley mounted on the arm; as set forth.

35. 2. In paper making machinery, a section drive comprising a lever with fulcrum therefor, rope pulleys mounted on said lever, and a belt pulley also mounted on said lever, together with means for swinging the lever about said fulcrum; as set forth.

40. 3. Paper-making machinery including a plurality of sections and belt drives for each section with means for adjusting the tension of the belts; as set forth.

45. 4. In paper making machinery, in combination with a section drive, a starting and stopping device, together with speed reducing means; as set forth.

50. 5. In paper making machinery, a machine section, a driven shaft in connection therewith, a driving shaft, pulleys on said shafts, friction means directly connecting said pulleys, and means for varying the position in space of one of said shafts; as set forth.

55. 6. In paper-making machinery a machine section, a driven shaft in connection therewith, a driving shaft, friction means connecting said shafts with means for varying the position in space of one of said shafts; as set forth.

60. 7. In paper-making machinery a machine section, a driven shaft in connection therewith, a driving shaft, friction means connecting said shaft with means for varying

the position in space of said driving shaft; as set forth.

65. 8. In paper making machinery a lever and fulcrum therefor, a driving shaft journaled in said lever, a pulley mounted on said driving shaft, a driven shaft disposed above said driving shaft with a pulley thereon, friction means connecting said driving and said driven shafts, a machine section and a mechanical connection from said driven shaft to said machine section; as set forth.

70. 9. In paper making machinery a lever and fulcrum therefor, a driving shaft journaled in said lever, a pulley mounted on said driving shaft, a driven shaft disposed above said driving shaft with a pulley thereon, a belt drive connecting said driving and said driven shafts, a machine section and a mechanical connection from said driven shaft to said machine section; as set forth.

75. 10. In paper making machinery a lever and fulcrum therefor, a circular rack mechanically connected to said lever, a pinion disposed to co-operate with said rack and means for rotating said pinion, a driving shaft journaled in said lever, a pulley mounted on said shaft, a driven shaft disposed above said driving shaft with a pulley thereon, friction means connecting said driving and said driven shafts, a machine section and a mechanical connection from said driven shaft to said machine section; as set forth.

80. 11. In paper making machinery a driven machine section, a shaft in connection therewith, a driving shaft, a pivoted frame adapted to carry said driving shaft, said driving shaft and frame being disposed at a lower level than the driven shaft and means situated at the level of the driven shaft for rocking said frame, as set forth.

85. 12. In paper making machinery a machine section a driven shaft in connection therewith and a cone pulley mounted thereon, a driving shaft disposed directly below said driven shaft with a cone pulley mounted thereon, a belt connecting said cone pulleys, further pulleys mounted on said driving shaft adapted to receive ropes, a frame carrying the bearings for said driving shaft, a fulcrum about which said frame can move, a circular rack connected to the frame, a pinion disposed in proximity to said rack and means for rotating the pinion, as set forth.

90. In testimony whereof I have signed my name to this specification in the presence of two subscribing witnesses.

ROBERT GIBB HUTCHISON.
